SNOUT PULLER

Oscar C. Schmidt, Cincinnati, Ohio, assignor to
The Cincinnati Butchers' Supply Company,
Cincinnati, Ohio, a corporation of Ohio

Application July 11, 1938, Serial No. 218,709

20 Claims. (Cl. 17—1)

My invention relates to snout pullers for pulling the snouts of hogs and the like in the butchering industry.

It is the object of my invention to provide new and improved pulling means for the snout, to provide new and improved means whereby to position the head of the animal of which the snout is to be pulled with relation to the pulling implement; to provide new and improved releasing means for the pulled snout; and to provide new and improved mounting means and adjusting means for the respective parts of my improved device.

My invention consists in new and improved means for accomplishing these objects; further, in a rotating disk on the face of which a snout pick is arranged to pull the snout during rotation of the disk; further, in so arranging the face of the disk with relation to the pick that said face serves as a support for the snout in a plane transverse to the axis of rotation of the disk to steady the snout end of the head with relation to the path of the pick in order to have the pick properly engage the snout; further, in a novel support for the head; further, in novel stripping means to release the pulled snout from the pick, and novel operating means for the same; further, in novel means for adjusting the operating means and for controlling the moment of release of the snout from the pick; and, further, in a novel mounting for the operating disk and novel adjusting means for the latter.

The invention will be further readily understood from the following description and claims, and from the drawings, in which latter:

Fig. 1 is a front elevation of my improved device.

Fig. 2 is a side elevation of the same, partly broken away.

Fig. 3 is an enlarged horizontal section of the same, taken on the irregular line 3—3 of Fig. 1, and partly broken away.

Fig. 4 is a vertical section of a detail of the driving means of my improved device, taken in the plane of the line 4—4 of Fig. 2.

Fig. 5 is a vertical section of my improved device, taken on the line 5—5 of Fig. 1, with the protecting shield removed.

Fig. 6 is a plan view of the support for the carcass head, partly in section on the irregular line 6—6 of Fig. 5, and partly broken away.

Fig. 7 is a rear view of the same in association with the snout pulling disk, partly in section in the plane of the line 7—7 of Fig. 6, and partly broken away; and

Fig. 8 is a side elevation, partly in section, showing a fragmentary view of the snout pulling disk, the support and the head of a hog in association therewith, the head of the hog being marked or slit to define the line of severance between the skull portion of the skin, fat and meat and the jaw portion thereof.

A frame 11 is provided with a top 12, rigidly connecting the ends 13, 14 of the frame, the ends being also connected by lower cross-bars 10 15, 16, bolted to said ends.

A snout pulling head or disk 21 is suitably rotatively mounted and driven. It is exemplified as comprising a face plate 22, from the margins of which an outer peripheral flange 23 extends rearwardly, strengthening ribs 24, 25, 26 being provided on the back of said face plate, and segmental ribs 27 on said back connecting said ribs. The face plate or disk is substantially round.

The disk is provided with a snout pick 31. Two of these snout picks are shown on the disk at diametrically opposite positions thereon. The snout pick is shown as comprising a base 32, which has picking prongs 33 projecting therefrom, the picking prongs having a space 34 between them, and the prongs being separated from the disk by spaces 35. The snout pick is secured in a shouldered groove 29 in the face of the disk by means of bolts 36, which extend 20 through lugs 30 on the disk from the rear thereof and are threaded into the base of the pick for firmly securing the pick to the disk, the shoulders 25 32 between the snout pick and the disk resisting 30 the blows upon the pick.

The picks on the opposite sides of the disk have their prongs projected in opposite directions when viewed from the front of the machine, but they project rotatively in the same direction, so that as the disk is rotated the advance or entering 40 points or ends 37 of the prongs are projected forwardly in the direction of rotation of the disk so as to enter the nostrils 38 of the snout 39, when the snout pick reaches the position of the head 40 being operated on to sever or pull the snout 45 from the head during the continuing rotation of the disk, which severing is done with a downward and lateral pull to aid in the severing action after an initial forceful blow upon the snout.

A support 43 is provided for the carcass head, 50 the support having a downwardly curved or dished depression 44 therein, forming a preferably saucer-shaped wall 45 on which the neck end of the head is arranged to be supported, the shape of the wall conforming approximately to the 55

shape of said neck end, the outer margin of said neck end being firmed and confined by the lateral walls 46, 47 of said depression, and the rear wall 48 of the same, so as to provide a firm support for said neck end.

A trough 51 connects with said depression, and the head may be conveniently entered into said depression through said trough, the operator usually having a position in front of the outer 10 end of the trough, which is preferably open-ended. The bottom 52 of said trough preferably slants toward the depression 44, so that any liquid therein may flow into the depression, and the lower wall of the depression is provided with 15 a hole 53 through which the liquid therein may escape.

One or more positioning pins 54 are also preferably provided in the bottom of this support at the inner end of the trough for aiding in positioning the head, the positioning pins entering into the neck end of the head or having the front portion of the margin thereof bear against said pins, to additionally prevent shifting of said neck end on said support and to firm said neck 20 end on said support. The positioning pin is preferably a taper pin releasably secured in a tapered hole 55 in the bottom wall of the support for renewal or substitution of pins of different lengths to best hold heads of different sizes.

The support 43 for the head is on a bracket 56 which extends from the frame. The cross-bar 15 may be a part of this bracket, bolts 57 extending through slots 58 in said bracket to permit adjustment of said support toward and 30 from the disk and to secure the same in adjusted positions. The bracket extends across the plane of the disk but is spaced from said disk by a space 59, and the support 43 is located in such spaced relation from the disk by a space 60 as to permit 35 the snout picks and the pulled snout thereon to pass between said disk and the inner end of said support.

The disk is provided with a bearing 64 rotatable about a stub shaft 65 having a head 66 between 40 which and the stub shaft proper there is a flange 67, the stub shaft being eccentric with relation to the head. The head is located in a bearing 68 in one of the end members of the frame, is rotatable in said bearing, and is clamped in adjustable positions in said bearing between said flange and a washer 69 and clamp nut 70 at the inner end of the head, the inner end of the head being threaded for receiving the nut. The adjustment of the head rotatively locates its eccentric stub shaft in desired position about the axis 50 of the head. A set bolt 71 is threaded through the bearing. Its inner end is received in an annular groove 72 in said head and is clamped against the bottom of said groove for aiding in clamping said head in said bearing and locating 55 said head endwise.

A pulley 75, shown as a sprocket wheel, is fixed to the disk, being located in an annular rabbet 76 in the inner end of the bearing 64 of the disk, 60 upon the reduced inner end 77 of said bearing against a shoulder 78 thereon and clamped to said disk by clamp bolts 79 passing through holes in said sprocket wheel and threaded into threaded holes in the bearing of the disk.

The driving means for the machine are exemplified as an electric motor 80 secured in hanging relation to the top of the frame. For securing adjustable positioning of the motor, the motor is mounted on an adjustable motor plate 81, 70 shown as a pivoted plate provided with bearings

82. Lugs 83 extend downwardly from the top 12 and are provided with bearings 84 which register with the bearing 82. A pivot rod 85 is located in said bearings for pivotally supporting the motor plate for the electric motor, the pivot 15 rod being held in axial direction by a set bolt 86, threaded in one of said bearings. A threaded stud 87 is fixed in the top 12 and extends through a hole 88 in the motor plate. Nuts 89, 90 threaded about said stud at opposite faces of said motor 10 plate adjust the motor plate and clamp the same in adjusted positions.

The rotor shaft 93 of the motor has a pulley 94 secured thereto, a flexible drive connection 95 being received thereabout and about a pulley 96 15 on a shaft 97 of a speed-reducing device 98 mounted on the frame. These pulleys are exemplified as sprocket wheels, and the flexible connection is consequently a sprocket chain. Adjustment of the motor plate 81 adjusts the tension of the flexible drive connection.

The speed-reducing device is exemplified as comprising a separable frame having a supporting member 101 provided with feet 102, through 20 holes 103 in which fastening bolts 104 pass into threaded holes in the top plate 12 for securing the speed-reducing device on the frame with relation to the motor and the disk to be driven thereby, the holes 103 being enlarged with relation to the fastening bolts 104 for permitting 25 shifting of the speed-reducing device on the frame, washers 105 being located between the heads of said bolts and the feet 102 for insuring clamping of said feet in various adjusted positions 30 of the speed-reducing device.

The shaft 97 is exemplified as a worm shaft and is journaled in bearings 106, 107 in the supporting member of said speed-reducing frame, and has a worm 108 fixed thereto, the hub of 35 which has end contact with end thrust bearings 109, 110, shown as ball bearings, located between the ends of said hub and the inner ends of said bearings 106, 107.

A worm wheel 115 is fixed to a shaft 116 journaled in bearings 117, 118 in the frame 98. These 40 bearings are shown as split bearings, parts whereof are located respectively in the supporting member 101 of the frame 98 and in a cap member 119 of said frame, the cap member being secured to the supporting member by means of bolts 120 45 passing through holes in lugs 121 in said members and having clamp nuts 122 threaded to their threaded ends. The supporting member and the cap member have enveloping walls 123 for enclosing the worm and worm wheel.

The shaft 116 is arranged to drive a pulley 125 concentric thereabout, and so connected therewith as to part the driving connection upon excess resistance by the snout pulling disk. Thus a bushing 128 is fixed to the shaft 116 as by a key 60 129 and by means of countersunk set screws 130 threaded in said bushing against said key and the shaft 116, for fixing the bushing rotatively and axially to said shaft. The pulley 125 is provided with a hub 131 located about the outer 65 periphery of the bushing 128 and held endwise to the latter by means of a bolt 132 threaded in the hub 131, the inner end of the bolt being located in an annular groove 133 in the bushing 128 to position the pulley endwise.

The bushing 128 is provided with a radially extending flange 134, having a radial enlargement as an arm 135 which extends alongside the pulley 125, said arm and said pulley being provided with registering holes in which a shear 70 75

pin 136 is located and held endwise by nuts 137 over its threaded ends. Upon excess resistance to the drive, the shear pin is sheared to prevent accident.

5 The shaft 116 is held endwise in its bearing by having the inner end of the bushing 128 bear against one end of said bearing, a collar 138 being fixed, as by a set bolt 139, to said shaft, the collar bearing against the other end of said bearing for holding the shaft endwise in said bearing.

10 A flexible driving connection, shown as a sprocket chain 141, is received about the pulleys 75, 125, exemplified as sprocket wheels, for driving the snout pulling disk by means of said speed reducing device. A protecting cover 140 is located about said sprocket chain 95 and pulleys 94, 96, and is suitably secured to the frame.

15 The snout pulling head or disk has strippers mounted thereon to strip the pulled snouts from the snout picks at a suitable radial point about the axis of the snout pulling disk to deliver the snouts as desired upon an operating table 145 or for other disposition, as may be desired. Two of such strippers are shown coacting with the respective snout picks. The strippers exemplified each comprises an arm 146, operating as a lever, and pivoted by a bearing 147 on a shoulder bolt 148 threaded into the rear of the pulling disk. This arm has a stripper finger 149 extending therefrom through a slot 150 in the disk and into the space 34 between the prongs 33 of the snout pick, this finger being located normally at the base of said space between the bases of the picking prongs of the snout pick. The other end of the 20 arm is provided with an actuating lug 153 extending therefrom through a hole 154 in the pulling disk and into the range of a coacting knock-out 25 155.

30 This knock-out is exemplified as an arm 156 secured to the eccentrically mounted stub shaft 65, being angularly adjustable and fixed to said stub shaft by a clamp bearing 157 of said arm, arranged to be clamped in adjusted positions about said stub shaft by a clamp bolt 158 rotatable 35 in one of the lugs 159 of said clamp bearing and threaded into the other lug of said clamp bearing.

35 A knock-out roller 160 is journaled on a shoulder bolt 161 threaded in a threaded hole 162 of said knock-out arm and held in place by a jam nut 163. The actuating lug 153 of the stripper lever contacts said roller for actuating the stripper lever and moving its stripper finger in the slot 150 from the base ends of the picking prongs to the outer ends of the latter for stripping the snout on 40 said picking prongs off of the same for further disposition of the snout.

45 A spring 165, the respective ends of which are secured to the heel end of the stripper lever and the body of the disk, normally returns the stripper finger to normal position at the base ends of the picking prongs as soon as the knock-out end of the stripper lever has passed its actuating member, or knock-out roller, regardless of the angular position of the actuating member. The knock-out 50 lug may be provided with a bevel face 166, terminating in a rounded portion 167 for smoothness of operation. The pulling disk is exemplified as rotatable in the direction of the arrow *a* during operation.

55 The outer end of the stub shaft has a portion 168, polygonal in cross-section, for receiving a suitable wrench for rotating the stub shaft to position the same angularly with relation to its bearing 68 for adjustably positioning the axis of 60 rotation of the snout pulling disk and for holding

the stub shaft while its head is being clamped in said bearing.

65 The head 40 of the carcass may at each side thereof be provided with an incision 169 extending through the skin and such portion of the fat and meat of the head as may be desired and preferably to the gristle and bone of the head and be of such form as to mark the portion of the skin, fat and flesh which it is desired to have pulled from the head upon pulling of the snout. These incisions 10 are exemplified as extending throughout the full length of the head but may be shorter and connected across the top of the head for pulling shorter portions of the head with the snout as may be desired. These incisions may be dispensed with.

15 In operation, the neck end of the head is placed on the support with its margin confined between the walls or flanges 46, 47 and 48 to firm said margin, the pins 54 aiding in such positioning and firming. The head is placed with its snout resting against the front face of the disk, forming a convenient means for positioning the snout with relation to the picking prongs in advance of the arrival of said prongs at the snout position. 20 Upon arrival of one of the snout picks at the position of the snout, the picking prongs enter the snout, for instance, the nostrils thereof, and exert a blow and pressure thereon to tear the snout and that portion of the skin, fat and meat at the top of the head which it is desired to sever from the balance of the head as the snout pick advances in its rotation about the axis of the disk. 25

30 The snout pick strikes the snout when descending at a position above the level of the axis of the disk, which position or point of striking contact with the snout of a usual size head is approximately at an angle intersecting said axis in a range of thirty to forty degrees from the horizontal plane in which said axis is located, but may 35 vary at greater or less angles depending on the size of the head, providing extreme range of sizes of heads for which my improved device is adapted.

35 The snout is supported on the front face of the disk preparatory to its being struck by the snout pick throughout the entire range, and the action 40 of the pick on the head is throughout that arc of the circle which is most nearly downward with relation to the support 43, so that the resistance of the support to the blow is most nearly upright 50 with relation to the bottom of the support to make the blow and severing action of the snout pick most effective.

45 The pulling of the snout and the portions of skin, fat and meat therebelow and at its sides 55 proceeds with the advance of the snout pick, which has a downward lateral arcuate path, for stripping the snout and its attached portions with a downward and lateral movement to enhance the ease with which said stripping takes place 60. The snout pick and the snout and the attached portions pulled thereby, move in the space 171 between the disk and the head being operated on and in the space 60 between the disk and the inner end of the support. The snout and its 65 attached portions are confined by the disk, the head and the inner end of the support, and are held forwardly by the front face of the disk. The pulled portion is bent across the rear wall 48 of the support, which aids in peeling the same from 70 the head and providing a clear severance thereof from the head, the position of the neck end being maintained by its location in the depression of its support and protuberances 172 in the bottom wall thereof, as well as by the walls about the 75

same, and the locating pins 54 at the rear of the head position, which aid in firming the margin of the neck end of the head.

The severed snout moves with the snout pick 5 until it is stripped therefrom by the stripper, and the stripper acts at the desired angular point in its path, depending on the further operation desired upon the pulled snout. This angular point may be adjusted by adjusting the position of the 10 knock-out arm about the axis of the snout disk. In the relation shown in Fig. 1, the stripping will take place when the snout pick arrives at approximately the bottom of its path of rotation, for discharging the severed snout upon the table 15 145 in position for having an operative perform such trimming operations as desired upon the severed snout, as, for instance, severing the meat and fat therefrom and suitably depositing the same and disposing of the gristle and skin and 20 other portions of the snout. The remaining portion of the head is removed from the support and placed on the table or otherwise disposed of for subsequent operations thereon.

The adjustment of the axis of the snout disk 25 about the axis of the head of the stub shaft, positions the disk laterally with relation to the support 43, for adjusting the path of the snout pick with relation to the support for the head. Angular adjustment of the stripper arm provides 30 for adjustment of the release position of the severed snout about the axis of the snout disk, determining the stripping moment, for depositing the snout at desired distance from the head support 43. The speed-reducing mechanism and the 35 driving connections are preferably such as to impart approximately seven and one-half revolutions per minute to the snout pulling disk, which has been found a desirable speed with the employment of two snout picks placed diametrically 40 opposite each other on the pulling disk.

It will be noticed that in my improved device the support for the head as well as the pulling disk overhang laterally beyond the frame of the machine, so as to provide clear space at the sides 45 and front of the same, as well as below the same, for ready manipulation of the head being operated on, and of the pulled snout. The placing of the snout picks on the face of the disk permits such exposed mounting of the snout disk 50 and the support for the head to be obtained, and enables the head to be positioned in such manner that the snout of the animal, before being pulled, is guided against the face of the disk so as to be in proper position for engagement of the 55 snout pick therewith.

It further comprises a compact device which may be supported in suitable position on the operating table, being preferably bolted thereon, so that the operator has free space on the table 60 about the machine for conveniently and quickly placing the head on the support of the machine, and for the passing the head from the support, after the snout has been pulled, to the table in convenient position for being operated upon by 65 an operative who trims such portion of the head as may be desired preparatory to the next operation on the head, which is usually that of separating the jaw from the top of the head.

I claim:

70 1. A snout puller comprising a rotatable pulling disk provided with a snout pick projecting in the direction of the axis of rotation of said disk outwardly from the face of said disk and rotatable with said disk, the said face extending transversely to the axis of rotation of said disk and

being a supporting guide against which to rest the snout end of the head of the carcass to position said snout in the rotary path of said snout pick preparatory to being struck by said snout pick. 5

2. A snout puller comprising a rotatable pulling disk provided with a snout pick projecting in the direction of the axis of rotation of said disk outwardly from the face of said disk and rotatable with said disk, the said face being a supporting guide extending transversely to the axis of rotation of said disk against which to supportingly guide the snout end of the head of the carcass to position said head with relation to the rotary path of said snout pick, and constructed to strip said snout and the portions adhering thereto with a downward and lateral movement transversely to said head. 10 15

3. A snout puller comprising a rotatable pulling disk provided with a snout pick projecting in the direction of the axis of rotation of said disk outwardly from the front face of said disk and rotatable with said disk, and a support having a supporting seat for the neck end of the carcass head in front of said disk and spaced by a space from said front face for the leaning of a carcass head supported on said seat past said space against said front face for coaction of the snout end of said head with said front face of said disk 20 25 as a guide in the path of said snout pick for coaction of said snout pick with the snout. 30

4. A snout puller comprising a frame, a pulling disk mounted to rotate in overhanging relation outwardly from said frame above the level of the bottom of said frame, and a snout pick 35 on said pulling disk provided with picking prongs projecting forwardly of the front face of said pulling disk and rotatable with said pulling disk, said front face being a supporting face for the snout of the carcass head, and said front face 40 and said picking prongs rotating in parallel planes perpendicular to the axis of rotation of said pulling disk spaced from each other along said axis.

5. In a snout puller, the combination of a 45 rotatable pulling head provided with a projecting snout pick, a snout stripper mounted on said head and comprising a stripper finger operating adjacent to said snout pick to strip the pulled snout therefrom, a knock-out part with which 50 said snout stripper coacts for stripping movement of said stripper finger to strip the snout, and adjusting means to time the angular position of said stripper at the moment of stripping movement of said stripper finger. 55

6. In a snout puller, the combination of a rotatable pulling head provided with a projecting snout pick rotatable with said head, a snout stripper mounted on said head and rotatable therewith and comprising a stripper finger operating adjacent to said snout pick to strip the pulled snout from said snout pick, a knock-out part for said snout stripper, means whereby to angularly adjust said knock-out part to adjust the moment of stripping movement of said stripper, and means to return said stripper to normal position immediately after stripping movement thereof regardless of the angularly adjusted position of said knock-out part. 60 65

7. In a snout puller, the combination of a 70 pulling disk, a snout pick on said pulling disk projecting outwardly from the outer face of said disk, a snout stripper pivoted on said disk and comprising a stripper finger coacting with said snout pick and an operating lug, said stripper 75

finger and said operating lug projecting outwardly beyond said outer face, and a knock-out at said outer face to operate said snout stripper for stripping the pulled snout from said snout pick.

8. In a snout puller, the combination of a pulling disk, a snout pick on said pulling disk projecting outwardly from the outer face of said disk, a snout stripper pivoted on said disk and comprising a stripper finger coacting with said snout pick and an operating lug, said stripper finger and said operating lug projecting outwardly beyond said outer face, a knock-out at said outer face to operate said snout stripper for stripping the pulled snout from said snout pick, and means to adjust the angular position of said knock-out about the axis of said pulling disk to adjust the moment of stripping movement of said stripper finger.

9. In a snout puller, the combination of a pulling disk, a snout pick thereon projecting outwardly from the outer face of said disk, a stripper lever at the inner face of said disk pivoted to said disk and comprising a stripper finger and an operating lug projecting through said disk, said stripper finger coacting with said snout pick, a spring to normally retract said stripper lever, and a contact part at the outer face of said disk with which said operating lug coacts to operate said stripper lever.

10. In a snout puller, the combination of a pulling disk, a snout picker thereon projecting outwardly from the outer face of said disk, a stripper lever at the inner face of said disk pivoted to said disk and comprising a stripper finger and an operating lug projecting through said disk, said stripper finger coacting with said snout pick, a spring to normally retract said stripper lever, a contact part at the outer face of said disk with which said operating lug coacts to operate said stripper lever, and means for angular adjustment of said contact part about the axis of said pulling disk to adjust the stripping moment of said stripper lever.

11. In a snout puller, the combination of a rotatable pulling head provided with a projecting snout pick rotatable with said head, a snout stripper mounted on said head and rotatable therewith and comprising a stripper finger operating adjacent to said snout pick to strip the pulled snout from said snout pick, a knock-out part for said snout stripper, means whereby to angularly adjust said knock-out part about the axis of rotation of said pulling head to adjust the moment of stripping movement of said stripper, a flexible driving connection for rotating said head, and means for adjusting the transverse position of the axis of rotation of said pulling head to adjust the tension of said flexible driving connection during maintenance of angular adjustment of said knockout part.

12. In a snout puller, the combination of a frame, a pulling disk, a stud mounted in said frame and having a portion projecting outwardly beyond said frame, said pulling disk journaled on said stud to overhang beyond said frame, a speed reducing device for said pulling disk mounted on said frame, driving means between said speed reducing device and said pulling disk, and snout pulling means on the face of said pulling disk distanced from said frame.

13. In a snout puller, the combination of a frame, a pulling disk, a stud mounted in said frame and having a portion projecting outwardly beyond said frame, said pulling disk journaled

on said stud to overhang beyond said frame, speed reducing means for said pulling disk mounted on said frame, flexible driving means between said speed reducing means and said pulling disk located in a plane parallel with said pulling disk between said frame and said pulling disk, means to adjust said stud laterally for adjusting the tension of said flexible driving means, and snout pulling means on the face of said pulling disk distanced from said frame.

14. In a snout puller, the combination of a pulling head, a snout pick on said pulling head, a snout stripper on said pulling head and comprising a stripper finger coacting with said snout pick to strip the pulled snout from the latter, a contact part with which said snout stripper engages to move said stripper finger to strip the pulled snout from said snout pick, and means whereby to adjust the contact moment between said snout stripper and said contact part.

15. In a snout puller, the combination of a rotatable pulling head, a snout pick on said pulling head, a snout stripper on said pulling head and comprising a stripper finger coacting with said snout pick to strip the pulled snout from said snout pick, a contact part with which said snout stripper engages to move said stripper finger in stripping direction, and means whereby to adjust said contact part angularly with relation to said rotatable pulling head to control the contact moment between said snout stripper and said contact part and thereby to determine the angular position of said snout pick at the moment of stripping movement of said stripper finger.

16. In a snout puller, the combination of a rotatable pulling disk having a snout supporting face, a snout pick mounted in said face and rotatable with said pulling disk, a support for the carcass head coacting with said supporting face to support the carcass head, said support being provided with a depression for the neck end of said carcass head and upstanding walls for the inner and side margins of said depression to firm said neck-end in said depression, and firming pins at the outer margin of said depression.

17. In a snout puller, the combination of a rotatable pulling disk having a snout supporting face, a snout pick mounted in said face and rotatable with said pulling disk, and a support for the carcass head coacting with said supporting face to support the carcass head, said support being provided with a depression for the neck end of said carcass head and a deflecting wall at the margin of said depression between said depression and said supporting face to deflect the tail end of the snout being pulled by the snout pick during rotation of said pulling disk.

18. In a snout puller, the combination of a rotatable pulling disk having a snout supporting face, a snout pick mounted in said face and rotatable with said pulling disk, a support for the carcass head coacting with said supporting face to support the carcass head, said support being provided with a depression for the neck end of said carcass head, and a trough extending forwardly from said depression and slanting toward said depression to drain into said depression, and the lower wall of said depression provided with a drain opening.

19. In a snout puller, the combination of a rotatable pulling disk provided with a front supporting face for the snout of the carcass head substantially perpendicular to the axis of rotation of said pulling disk, a snout pick on said

pulling disk in the cylindrical plane of said front supporting face, and a support for the carcass head, said support being provided with a depression for the neck end of said carcass head partly 5 inside and partly outside said cylindrical plane, constructed for having the carcass head supported by the wall of said depression at its neck end and by said front supporting face at its snout end.

20. A snout puller comprising a frame, a stud 10 on said frame projecting outwardly beyond said frame, a pulling disk mounted on said stud in overhanging relation outwardly from said frame,

a snout pick on said pulling disk projecting forwardly from the front face of said pulling disk, a speed reducing device on said frame, and a flexible driving means extending outwardly beyond said frame between said speed-reducing device and said pulling disk and comprising a partible driving connection to part upon excess resistance between said snout pick and the carcass head being operated on to protect said overhanging parts from damage. 10

OSCAR C. SCHMIDT.
